UNITED STATES PATENT OFFICE.

WILLIAM H. BROWN, OF CLEVELAND, OHIO.

DUST-GUARD FOR AUTOCARS.

SPECIFICATION forming part of Letters Patent No. 742,580, dated October 27, 1903.

Application filed August 13, 1903. Serial No. 169,350. (No model.)

To all whom it may concern:

Be it known that I, WILLIAM H. BROWN, a citizen of the United States, residing at Cleveland, in the county of Cuyahoga and State of Ohio, have invented a certain new and useful Improvement in Dust-Guards for Autocars, of which the following is a full, clear, and exact description, reference being had to the accompanying drawings.

10 Riders in autocars traveling on dusty roads are subjected to great annoyance and discomfort by the dust which is stirred up by the car and surges over the top of the rear end thereof. The car in its forward movement, especially 15 if it is moving rapidly, creates air-currents beneath it which stir up the dust, and it also creates behind it a partial vacuum. The dust-laden air from beneath the car rushes up behind it to fill this partial vacuum and as a 20 result deposits or almost throws the dust over the rear top edge into the car and upon the passengers. To prevent this, a shield has been extended out behind the car; but such a shield is not only an imperfect expedient, 25 but it is also unsightly and is in the way, especially on a touring-car of the Tonneau type, since it must be displaced to permit the rear door to be opened.

The object of this invention is to prevent 30 the dust-laden air from flowing over the top of an autocar, especially at the rear end thereof, and to accomplish this result by simple means which are not in the way and do not look badly.

35 The invention consists, broadly, in the combination, with an autocar, of curved open-ended air-conduits which extend a short distance along each side of the car and curve around its rear end a short distance, whereby 40 air is discharged from its rear end crosswise of the car and close to its rear end.

It also consists in the more specific construction and combinations of parts shown in the drawings and hereinafter described and 45 claimed.

In the drawings, Figure 1 is a perspective view of one side of the rear end of an automobile touring-car, and Fig. 2 is a plan view of the rear end of said car.

50 Referring to the parts by letters, A repre-

sents the autocar-body, which is of familiar form, and B represents the rear mud-guards, which are secured to said body near the rear end thereof.

C represents a thin sheet, preferably of 55 metal, which extends along the side of the car for a short distance and then curves around about the rear end thereof, following substantially the curvature of the car-body. This sheet, as shown, extends from the mud-guard 60 up to about the level of the top of the carriage-body, and the sheets are held in place by suitable bracket-arms c. One of such sheets is secured on each side of the body. The result of so placing these sheets in the position described is that there is formed between them and the carriage-body air-conduits having open front ends, into which air must necessarily flow as the carriage moves forward, and having open rear ends directed crosswise of the 65 carriage and behind the same. The air-currents which flow into the front ends of these conduits are deflected and are discharged across the rear end of the car in a zone near the upper edge thereof. This air 70 is taken from a considerable distance above the ground, where it is not laden with dust raised by the carriage itself. As it flows from the rear end of these conduits it relieves the 75 partial vacuum behind the car near the upper edge thereof. Because of this fact the dust-laden air which rushes up behind the car to fill the partial vacuum is checked and held down by this zone of relatively pure air delivered from these conduits and does not, 80 therefore, flow over the rear top edge of the car. The tops of these conduits are open in the construction shown, and it is believed that the apparatus is more efficient when they are so opened, because relatively pure air is 85 discharged from their said tops for substantially their entire length, wherefore the protecting zone of pure air is practically coextensive with the conduits; but this is not regarded as a material characteristic of the 90 generic invention. It will also be noticed that the lower part of the front end of the conduits are closed, and it is thought that it is of 95 advantage to have the lower parts closed to the extent shown, because the upward flow of 100

air into said conduits at the sides of the car is thereby prevented, and the mud-guards form a convenient means for so closing them.

Having described my invention, I claim—

- 5 1. The combination with autocar, of an open-ended air-conduit secured to the car-body and extending a short distance along the side and around the end thereof, whereby the rear end is directed crosswise of the car, substantially as and for the purpose specified.
- 10 2. The combination with an autocar, of two open-ended air-conduits secured respectively to the sides of the car and extending a short distance around the rear end thereof toward each other, substantially as and for the purpose specified.
- 15 3. The combination with an autocar, of a curved sheet secured to the car-body a short

distance therefrom and extended along the side of the car and around the rear end thereof, substantially as and for the purpose specified.

4. The combination with an autocar and its rear-wheel mud-guards, of two curved sheets secured to the body above and close to said mud-guards and a short distance from said body, said sheets extending along the sides of the car and a short distance around the rear end thereof, substantially as and for the purpose specified.

In testimony whereof I hereunto affix my signature in the presence of two witnesses.

WILLIAM H. BROWN.
